TELEVISION RECEIVING SYSTEM

Albert Bouwers, Eindhoven, Netherlands, assignor, by mesne assignments, to Radio Corporation of America, New York, N. Y., a corporation of Delaware

Application October 9, 1937, Serial No. 168,122
In the Netherlands November 9, 1936

4 Claims. (Cl. 178—7.5)

The invention relates to a television receiving system, more particularly to a system in which use is made of a cathode-ray tube and which comprises a device for deflecting the cathode ray beam in a direction parallel to the scanning lines and wherein preferably a second device is provided for deflecting the beam in a direction perpendicular to the scanning lines.

With the existing television systems it is generally customary to utilize in the transmitter a device by which the picture to be transmitted, or an image of the picture, is scanned at a uniform speed and wherein a current is obtained which fluctuates in dependence on the brilliancy of the picture elements which are successively scanned while the picture currents thus obtained are modulated on a carrier wave and are transmitted. With the receivers adapted to receive oscillations thus transmitted and comprising a cathode-ray tube, the picture currents received are supplied, after detection, to an electrode of the cathode ray tube which controls the intensity of the cathode ray beam generated in the tube while the cathode ray beam is moved by at least one device for deflecting the cathode ray beam at a uniform speed over a screen arranged within the tube.

A second method of transmitting pictures consists in scanning the picture to be transmitted at a speed which is determined by the brilliancy of the picture elements of the picture to be transmitted which are successively scanned whereupon in dependence on said speed a carrier wave is modulated and emitted. In the corresponding receiver the oscillations obtained after detection are supplied to the device for deflecting a cathode ray beam in a direction parallel to the scanning lines with the result that the cathode ray beam is moved at the receiver at a variable speed over a screen arranged within the tube, said speed being dependent on the brilliancy of the corresponding picture elements of the picture to be transmitted. The use of the last-mentioned system entails a considerable disadvantage which resides in that the time during which an entire line or an entire picture is scanned is not constant so that particular measures are necessary to ensure synchronism between the picture transmitter and receiver.

This invention is based on the recognition that with the use of the last mentioned scanning method, which will hereinafter be referred to as "velocity scanning," a material intensification of the contrasts and a considerable increase of the average quantity of light emitted from the

picture reproduced is obtained if use is made of a cathode ray tube having a screen which becomes luminous upon electron bombardment and which has the property that there exists a non-linear relation between the time during which the electrons strike the screen (hereinafter referred to as "time of exposure") and the quantity of light emitted.

The invention is more particularly concerned with a television receiving arrangement in which the cathode-ray tube comprises a screen which becomes luminous by electron bombardment and has the property that a non-linear relation exists between the time during which the electrons strike the screen and the quantity of light emitted.

Cathode ray tubes which have a screen that emits light upon electron bombardment and wherein a non-linear relation exists between the time of exposure and the quantity of light emitted have previously been suggested in themselves for television purposes. One example of a tube wherein the screen has the characteristic curve desired is a tube which has a screen consisting of refractory material which is raised to incandescence by electron bombardment. Tubes having similar characteristics but with different screens may, of course, be used.

The system according to the invention consists, therefore, in a television receiving system of the kind wherein the received oscillations obtained after detection are supplied to the above-mentioned device for deflecting the cathode ray beam in a direction parallel to the scanning lines and wherein the cathode ray tube comprises a screen which becomes luminous when struck by electrons and which has the property that there exists a non-linear relation between the time during which the electrons strike the screen and the quantity of light emitted.

The invention has for its purpose, therefore, to procure an improvement of the television receiving arrangement above referred to, this improvement consisting in that a carrier wave, modulated by the received picture currents, is supplied to the deflecting means of the device for deflecting the beam of cathode rays in a direction parallel with the scanning lines.

The invention will be more clearly understood by reference to the accompanying drawing wherein:

Figures 1 and 2 each shows one form of construction of the circuit arrangement according to the invention; and

Figure 3 shows, for example, a response curve for a cathode ray tube screen.

- The television receiving arrangement represented in Figure 1 comprises a cathode ray tube 2 equipped with an electrode system for generating a beam of cathode rays and consisting at least of a cathode 4 and an anode 6. To deflecting plates 8 is supplied an alternating voltage which is produced by a device 10 for the deflection of the beam of cathode rays in a direction parallel with the scanning lines, herein-after called horizontal scanning device, said voltage having a saw tooth curve. In addition two deflecting plates 12 are provided to which is fed a saw tooth potential produced by a device 14 for deflecting the beam of cathode rays in a direction normal to the scanning lines, this device being herein-after called vertical scanning device. The receiving arrangement furthermore comprises an amplifier 16 to which are supplied the received modulated oscillations and which may be designed for frequency transformation of the received carrier waves. The oscillations occurring in the output circuit of the amplifier 16 are supplied to a detector 18, in the output circuit of which low frequency picture currents and synchronizing impulses occur, which impulses are transmitted for the purpose of synchronizing the saw tooth voltages produced by the devices 10 and 14. A filter 20 serves to separate the synchronizing impulses and the picture currents, whereas a filter 22 is provided for splitting up the synchronizing pulses into line pulses and picture pulses. The line impulses which are emitted by the transmitter at the end of each scanning line, are supplied to the horizontal scanning device 10, whereas the picture impulses which occur at the end of the scanning of each picture, are applied to the vertical scanning device 14. The low frequency picture currents set up in the output-circuit of the detector 18, if desired after having been separated from the synchronizing impulses, are modulated on a carrier wave generated by a local oscillator 24 and the modulated oscillations thus produced are supplied to the deflecting plates 8. The means for modulating the picture currents on the oscillations generated by the local oscillator 24, is designated by 26 in the drawing.
- Figure 2 shows a form of construction in which the modulated oscillations occurring in the output circuit of the amplifier 16 are supplied to the deflecting plates of a cathode ray tube without interposition of a detector. Otherwise the circuit arrangement exactly corresponds to that represented in Figure 1.

The operation of the circuit arrangement set out above is based on the fact that the cathode ray tube 2 comprises a screen which has the property that a non-linear relation exists between the time during which the electrons strike the screen and the quantity of light emitted as a function of the time during which the electrons strike the screen may consequently have a shape as illustrated in Figure 3, where L is the quantity of light emitted and T the time during which the electrons strike the screen, herein-after called time of exposure.

To the deflecting plates 8 is supplied a saw tooth potential which is generated by the device 10 and serves to deflect the beam of cathode rays in a direction parallel with the scanning lines, the period of which determines the scanning time of one scanning line. When superposing on this voltage a non-modulated oscillation, which is generated by the oscillator 24 whose frequency is preferably a multiple of the saw tooth potential generated by the device 10, the movement of the scanning beam in scanning each scanning line will be accelerated and retarded during each half cycle of the impressed oscillation. However, the total scanning time of a scanning line remains constant and equal to the period of the saw tooth potential generated by the device 10.

The time during which the electrons strike the screen is inversely proportional to the speed at which the scanning beam moves over the screen. During that part of the half cycle of the impressed oscillation, in which the movement of the scanning beam is accelerated, the time during which the electrons strike the screen is short, and during the retarded part of the half cycle of the impressed oscillation the time of exposure is long. If the curve indicating the quantity of light L emitted under bombardment by electrons as a function of the time T has the shape illustrated in Figure 3, then the emitted quantity of light increases with an increase of the time of exposure from the value T_1 to T_2 , i. e., during the retarded part of the half-cycle of the impressed oscillation, to a larger extent than the quantity of light emitted during the accelerated part of the half-cycle decreases due to the decrease of the time of exposure from T_1 to T_3 . From this it results that the average quantity of light emitted, indicated by the dash-and-dot line in Figure 3, is appreciably larger than if the scanning beam were moved at a uniform speed over the screen in which case the average quantity of light emitted would be determined by the time of exposure T_1 corresponding to said speed.

With an increase and with a decrease respectively of the amplitude of the oscillations fed to the deflecting plates 8 of the cathode ray tube 2, the acceleration and the retardation of the beam of cathode rays during each half cycle of the impressed oscillations increases and decreases respectively in accordance with the increase and decrease respectively of the amplitude of the oscillations; in other words the average quantity of light emitted during each cycle of the oscillations impressed on the deflecting plates 8 varies in accordance with the amplitude of these oscillations since the increase of the quantity of light emitted during that part of the half cycle of the impressed oscillations, in which the scanning beam is retarded, is always appreciably larger than the decrease during that part of the half cycle in which the scanning beam is accelerated.

In the circuit arrangement according to the invention the amplitude of the oscillations supplied to the deflecting plate 8 varies in accordance with the low frequency picture currents which are modulated on said oscillations so that a variation of the average quantity of light emitted during each cycle of the carrier wave is obtained, which variation depends on the low frequency picture currents modulated on the carrier wave.

Since the increase of the average quantity of light emitted during that part of the half cycle in which the scanning speed is retarded is much larger than the decrease of the average quantity of light emitted during that part of the half cycle in which the scanning speed is increased, an appreciable intensification of the contrasts in reproducing the picture in the manner set out above is obtained.

The explanation of the phenomenon that, with

the use of a cathode ray tube as above referred to in a television receiver wherein velocity scanning is utilized, an appreciable intensification of the contrasts and an increase of the average quantity of light emitted from the picture reproduced is obtained is based on the following.

The time during which the electrons strike the screen is inversely proportional to the velocity with which the screen is scanned. With a bright picture element the time during which the electrons strike the screen is long and with a dark picture element the time of exposure is short or vice versa. If the curve which represents the quantity of light L which is radiated upon electron bombardment as a function of the time of exposure has a shape as shown in Figure 3, the quantity of light emitted increases, with an increase of the time of exposure from the value T_1 to T_2 , that is to say during the reproduction 20 of a bright picture element, more strongly than the quantity of light emitted decreases, due to the decrease of the time of exposure from T_1 to T_3 , during the reproduction of a dark picture element. It results therefrom that the contrasts 25 between the bright picture elements and the dark ones are intensified while in addition the average quantity of light emitted, which is indicated in Figure 3 by a dot-and-dash line, is considerably larger than with the use of a screen with which 30 the relation between the time of exposure and the quantity of light emitted is linear and whereby consequently the average brilliancy remains constant.

It is not imperative that the curve indicating 35 the quantity of light emitted as a function of the time of exposure should have a shape as represented in Figure 3, where the quantity of light emitted increases more than proportionally with the time of exposure. If in reproducing a bright 40 picture element the amplitude of the carrier wave supplied to the deflecting plates 8 increases, and in reproducing a dark picture element the amplitude of the carrier wave fed to the deflecting plate decreases, the curve should have such a 45 shape that with an increasing time of exposure the quantity of light emitted decreases more than proportionally to the time. Also, in velocity scanning, if in the reproduction of a bright picture element the time during which the electrons 50 strike the screen is short and if during the reproduction of a dark picture element the time of exposure is long, the curve must have a shape such that with an increasing time of exposure the quantity of light emitted decreases more than 55 proportionally with time. In either case the contrasts between the light and dark picture elements are also increased, whereas the average quantity of light emitted is larger than when using a television receiving arrangement not in

accordance with this invention, in which the low-frequency picture currents control the intensity of the beam of cathode rays.

It is to be understood that, although electrostatic deflection means are shown, any form of 5 deflection, whether electrostatic, electrodynamic, or a combination of these, may be used.

Various modifications may be made in the invention without departing from the spirit and the scope thereof, and it is desired that any and 10 all such modifications shall be considered within the purview of the invention except as limited by the hereinafter appended claims.

I claim as my invention:

1. A television receiving arrangement comprising- 15
ing a cathode ray tube, means for producing a cathode ray beam in the tube, a screen adapted to emit light when subjected to electronic bombardment and having the property that a non-linear relationship exists between the time during 20 which the electrons strike the screen and the quantity of light emitted therefrom, means for deflecting the cathode ray beam in one direction at a constant frequency, means for generating a substantially high frequency carrier wave, means 25 for modulating the carrier wave by the received picture signals, and means for very rapidly varying the rate of deflection in accordance with the intensity of the modulated carrier wave.

2. A circuit arrangement as claimed in claim 1, 30
in which the frequency of the carrier wave which is supplied to the deflecting means of the device for deflecting the beam of cathode rays and modulated by the received picture currents is a multiple of the frequency of the current or voltage 35 supplied to the deflecting means by the said device.

3. A circuit arrangement as claimed in claim 1, 40
in which the screen of the cathode ray tube consists of a highly refractory material which is 45 brought to incandescence under bombardment by electrons.

4. A television receiving arrangement comprising a cathode ray tube, means for producing a stream of electrons in said tube, said tube including 45
a screen adapted to emit light when bombarded by the stream of electrons and which has the property that a non-linear relationship exists between the time during which the electrons strike the screen and the quantity of light emitted thereby, means for repeatedly deflecting the beam of electrons in substantially perpendicular directions at different constant frequencies to scan said screen, means for rapidly accelerating and decelerating the rate of deflection of the beam in one direction at a constant rate, and means for controlling the amount of acceleration or deceleration in accordance with the received picture signals. 50 55
